UNITED STATES PATENT OFFICE.

ANDREW B. ELLIOTT, OF TOLEDO, OHIO.

ELECTRIC FLUID-HEATER.

1,360,510.

Specification of Letters Patent. Patented Nov. 30, 1920.

Application filed April 19, 1920. Serial No. 375,024.

To all whom it may concern:

Be it known that I, ANDREW B. ELLIOTT, a citizen of the United States, residing at Toledo, in the county of Lucas and State 5 of Ohio, have invented certain new and useful Improvements in Electric Fluid-Heaters; and I do declare the following to be a full, clear, and exact description of the invention, such as will enable others skilled 10 in the art to which it appertains to make and use the same.

This invention relates to fluid heaters of the electrical type, and it has particular reference to one which is especially designed 15 for installation in one of the water circulating pipes leading from an automobile radiator to the engine, its purpose being to keep the water in the radiator at a temperature which will prevent it from freezing during 20 cold weather. The foregoing is one of the uses to which my invention may be put, although it is not to be restricted to this use.

The object of the invention is to provide a simple and effective heater of the above- 25 mentioned character which is easy to make use of, that is, to install; one which is durable and inexpensive to both the manufacturer and the user.

Other objects and advantages of the in- 30 vention will be apparent during the course of the following description.

In the accompanying drawings forming a part of the specification and in which like numerals are employed to designate like 35 parts throughout the same, the figure is a central vertical section view of a heater constructed in accordance with my invention, showing it installed.

In the drawings, wherein for the purpose 40 of illustration is shown a preferred embodiment of my invention, the numeral 1 designates a pipe through which water circulates. In this instance, however, this pipe is supposed to be either the outlet pipe or return 45 pipe of the water-circulating system of an automobile, in connection with which my invention is primarily intended to be used.

My heater comprises a shell 2 of tubular formation, preferably made of light metal, 50 such as aluminum made integral with or connected to the shell at its open end is a head 3 which is provided with a plurality of flat faces to permit the use of a wrench. To accommodate the shell for connection with 55 the pipe 1, I provide it with screw-threads 2°. The head 3 is counter-bored to provide

an annular internal shoulder 4, the purpose of which will hereinafter be described. Disposed within the shell is a sleeve 5 of insulation material, and this sleeve is provided at one end with a lateral flange 6 which rests on the shoulder 4, it being tightly clamped thereon by the nut 7 which coacts with the threaded portion of the counterbore. The nut 7 is provided with a hole which extends therethrough and in this hole a second sleeve 8, of insulation material is fitted. This hole permits passage of an electrode 9 therethrough. A heating coil 10 surrounds the electrode, one end thereof being grounded to the nut 7, while the opposite end thereof contacts the brass washer 11 carried by the electrode 9. If desired a core 12 of asbestos or the like may be inserted between the electrode and heating 75 coil. Current is supplied to the electrode by means of the wires 13 which lead to the battery 14, which may be the battery which is commonly used for supplying current to the ignition and lighting systems of the machine. The numeral 15 designates the switch 80 by means of which the heater is placed in operation.

In operation, it will be seen that after the electrical circuit has been closed by the 85 switch 15, current will be supplied to the heating coil, and the heat radiating therefrom will heat the shell 2. Hence, it will be seen that the water passing through the pipe 1 and coming into contact with the 90 shell 2 will be sufficiently heated to prevent it from freezing.

My heater is extremely simple in construction and consists of comparatively few and inexpensive parts, which are so arranged 95 that they may be readily disconnected for any purposes whatsoever. I desire to mention here, that my heater is not only to be used as a radiator heater, but it may be effectively used for various other purposes. 100 For instance, it may be used for boiling water in a receptacle or the like. It is to be understood that the form of my invention herein shown and described is to be taken as a preferred form of the same and that 105 various minor changes in the shape, size and arrangement of parts may be resorted to without departing from the spirit of the invention or the scope of the subjoined claim.

I claim:

A device of the class described compris-

ing a tubular shell open at one end and closed at its opposite end, being provided at its open end with an internal continuous shoulder adjacent to and above which are 5 internal screw-threads, a sleeve of insulation material disposed in the shell, being provided at its outer end with a lateral flange resting on said shoulder, and a removable heating unit arranged within said sleeve 10 and tube, said unit including a centrally apertured screw-threaded plug which is screwed into the threaded portion of the shell, serving to clamp the aforementioned lateral flange tightly against said shoulder, a second and relatively small sleeve of insulation material fitted in said aperture, this sleeve being also provided with a lateral

flange resting on the outer surfaces of the plug, an electrode extending through said last named sleeve and into said shell, a 20 washer on the inner end of the electrode, and a heating coil surrounding said electrode, one end thereof being grounded to the plug, the opposite end having electrical engagement with said washer; and an electrical connection on the outer end of said electrode, one of the parts of this connection serving to clamp the lateral flange of the second named sleeve tightly against said plug. 25

In testimony whereof I have hereunto set my hand:

ANDREW B. ELLIOTT.
